UNITED STATES PATENT OFFICE.

ANDREJ BRONSKI, OF EAST ST. LOUIS, ILLINOIS.

PORCH-SWING.

1,275,375.

Specification of Letters Patent. Patented Aug. 13, 1918.

Application filed December 30, 1916. Serial No. 139,812.

To all whom it may concern:

Be it known that I, ANDREJ BRONSKI, a subject of the Emperor of Austria, resident of East St. Louis, county of St. Clair, and 5 State of Illinois, have invented certain new and useful Improvements in Porch-Swings, of which the following is a specification.

This invention relates to improvements in lawn or porch swings, particularly those 10 of a portable character, and has as its principal object the provision of a swing adapted to be used by several persons at one time, and having means combined whereby a current of air may be produced, the air 15 being directed toward the occupants of the swing.

A further object is to provide a device of the kind which may be readily transported from place to place, the same being 20 used with entire safety, the fan elements being automatically operated by the involuntary action of the parties in operating the swing.

These and other like objects are attained 25 by the novel construction and combination of parts hereafter described and shown in the accompanying drawings, forming a material part of this specification, and in which:—

30 Figure 1 is a side elevational view of a swing made in accordance with the invention.

Fig. 2 is a vertical sectional view of the same.

35 Fig. 3 is a transverse sectional view taken on line 3—3 of Fig. 1, and

Fig. 4 is a partial sectional view, parts being broken away showing the transmitting mechanism.

40 The device consists of an essentially rectangular frame or base 10 comprised of side and end elements from which rise standards 11 at the corners, the same being further secured by braces 12, the standards 45 being attached at their upper ends to an awning frame 14 provided with a cover 15 by means of which the parties using the swing may be sheltered from the rain and sun.

50 Suspended from the frame 14 by pivoted rods 17 is a swinging frame 18 carrying a platform 20 provided with fixed foot rests 21 and supporting central standards 22 having braces 23 by which it is held perpendicular to the frame 18.

Also secured on the frame 18 are the lower elements 25 of seats 26 provided with backs 27 and 28 thereby forming a comfortable seat for the occupants of the swing.

One of the backs 28 has an extending 60 arm 29 containing a slot 30 at its lower end through which passes a pin 31 secured in one of the sides of the frame 18. Thus when the occupant of the seat leans back, the swing is caused to oscillate.

65 At the top of the standards 22 is a transverse shaft 35 upon which is mounted arms 36 carrying fan blades 37, a band or sprocket wheel 38 being secured alongside of the fan upon the shaft and adapted to be operated 70 by a band or chain 39 leading from the driving wheel 40, mounted on the shaft 42 journaled in the sides of the frame 18.

75 Also upon this shaft is loosely secured a ratchet wheel 44 engaged with which are pawls 45 pivoted on the side of the wheel 40 and held operatively in connection with the teeth of the ratchet by the springs 46.

Secured to the side of the ratchet wheel 44 is a pinion 48 engaging with a rack 49 80 formed near the outer end of a bar 50, pivotally engaged at its opposite end with one of the suspending rods 17.

85 Thus when the occupant leans back against the element 28, the swing platform 18, together with the elements mounted thereon, are caused to oscillate whereby the bar 50 is given a longitudinal motion, causing the rack 49 to communicate rotary motion to the pinion 48 and ratchet 44, and 90 by reason of the pawls, imparting a rotary motion to the driving wheel 40.

95 Obviously, when the swing oscillates in the opposite direction, the pawls will ride over the ratchet teeth 44 imparting no motion to it.

100 From the foregoing, it will be seen that means are provided whereby the fan is given intermittent rotary motion during movement of the swing, the fan operating at a speed proportional to the length of the oscillation of the frame 18 and the speed at which it is oscillated.

105 Obviously, the opposite seat may be similarly arranged with the rack bar and power transmitting device so that at each oscillation an impulse may be given to the fan, causing it to rotate in one direction uninterrupted.

Having thus described my invention, 110

what I claim as new, and desire to secure by Letters Patent, is:—

1. In a device as described, in combination, a base member, standards secured thereupon, an awning frame secured to the upper ends of said standards, pivotal rods secured to said awning frame, a swinging frame suspended upon said rods and carrying a platform, central standards secured 10 in transverse spaced apart relation upon said platform, a shaft journaled at the upper ends of said central standards, a fan secured for rotation upon said last-named shaft, means for rotating said shaft, a longitudinally-movable member adapted to actuate 15 said means, a chair secured upon one end of said platform, a chair back pivotally connected between its ends to one pair of said pivotal rods, said pivoted back engaging 20 with said swinging frame so as to turn upon its pivot, and a connection between said last-named rods and said member whereby said member obeys the movement of said rods.
2. In a device as described, in combination, a base member, vertical standards secured thereupon, an awning frame secured upon said standards, pairs of rods pivotally

mounted upon said awning frame, a swinging frame suspended upon said rods, said frame including a platform, a chair secured at one end of said platform, a back pivotally mounted upon one pair of said rods and having lower extending arms formed with elongated slots therein, a pair of central standards secured upon said platform, a shaft journaled upon the upper ends of said standards, a series of fan blades fixed upon said shaft, a second shaft arranged below said platform upon said swinging frame, a chain drive from the second shaft to the first shaft, a pinion also fixed upon the second shaft, a rack bar meshing with said pinion and guided against the underside of said platform, an eye formed at one end of said rack bar in which one of the pivotal rods project, a pin secured to the side of said swinging frame and projecting into the slot in the extending arm of said chair back, said chair back being inclined 45 with respect to the vertical when said pivotal rods are arranged parallel and vertically. 50

In testimony whereof I have affixed my signature this 22nd day of December, 1916.

ANDREJ BRONSKI.
